SET OF PLAYING CARDS

Cornell Saxon, 5 Halcyon Place, Yonkers, N.Y.

Filed Oct. 16, 1962, Ser. No. 72,123

Term of patent 14 years

(Cl. D34—13)

FIG. 1.

FIG. 2.

FIG. 1 is a top plan view of a set of playing cards, showing my new design; and

FIG. 2 is a top plan view of a pair of jokers included in the set of playing cards.

The rear surfaces of the cards are conventional.

The dominant features of the design reside in the portions shown in full lines.

I claim:

The ornamental design for a set of playing cards, substantially as shown and described.
